(21) Appl. No.: **29/157,505**

(57) **CLAIM**

(22) Filed: **Mar. 20, 2002**

I claim the ornamental design for a rim cover for protecting the rim of a wheel assembly during detailing of the tire, as shown and described.

(51) **LOC (7) Cl.** **12-16**

DESCRIPTION

(52) **U.S. Cl.** **D12/213**

FIG. 1 is a top plan view of a rim cover for protecting the rim of a wheel assembly during detailing of the tire, showing my new design;

(58) **Field of Search** D12/213, 204; D9/452, 454; D7/354, 358, 391, 392.1; 301/37.1, 37.26, 37.42, 108.1; 220/908, 912

FIG. 2 is a side view of the rim cover shown in an inverted position;

(56) **References Cited**

FIG. 3 is side view of the rim cover shown in an upright position;

U.S. PATENT DOCUMENTS

FIG. 4 is a bottom view thereof;
